UNITED STATES PATENT OFFICE.

TARY PACIFICO, OF BUFFALO, NEW YORK.

GLOVE.

1,329,996.

Specification of Letters Patent. Patented Feb. 3, 1920.

Application filed January 8, 1918. Serial No. 210,894.

To all whom it may concern:

Be it known that I, TARY PACIFICO, a citizen of Italy, residing at Buffalo, in the county of Erie and State of New York, have 5 invented certain new and useful Improvements in Gloves, of which the following is a specification.

This invention has reference to working gloves or mittens such as are commonly used 10 by mechanics, workmen, railway and street car operators, and other people handling machinery, tools and the like as well as for various uses in connection with the household or with the handling of chemicals or 15 the like where it is of importance to protect the hands against the action of injurious substances or excessive degrees of temperature, and has for one of its objects to improve the construction and increase the 20 utility of devices of this character.

An embodiment of the invention is shown in the accompanying drawings in which,—

Figure 1 is a perspective view, the glove being shown from the inside with the closing flaps open to show the clefts or openings, 25 and

Fig. 2 is a cross section through the thumb portion with the covering flap closed.

The improved glove is designed to overcome the difficulties hitherto experienced in 30 connection with gloves or mittens of the kind referred to, of handling articles which require the direct action of the touch of the skin, in order to secure a firm grip or to 35 prevent slipping in the hand of the operator. This is the case for instance when it becomes necessary to handle articles of comparatively small size, such as a watch, pieces of money, or to prevent slipping, such as 40 handling a screw driver, adjusting micrometer screws, small nuts or the like. With the gloves heretofore in use it became necessary to remove the glove for such purposes, entailing loss of time and the liability 45 of losing the glove. By my invention I am enabled to overcome this difficulty by providing any of the fingers of the glove or mitten with openings and suitable flaps, to be closed by suitable devices, and permitting 50 the operator to project his fingers through these openings which are preferably though not necessarily, arranged at the insides of about the middle of the thumb and forefinger of the gloves.

The glove or mitten may be made of rubber, leather, canvas, knitted or worsted material or any other kind of fabric, of oiled paper or the like.

In the present embodiment of the invention the holes or slots 1 and 2 respectively 55 are provided in the insides of the middle parts of the forefinger 3 and the thumb 4. These openings may be covered by side flaps 5 and 6 respectively which are secured by stitching or otherwise at the sides of the 60 openings, and may be secured by ordinary buttons or otherwise. In the preferred form 65 of construction shown in the drawings the flaps are of sufficient length to reach around the finger or thumb, so as to enable them 70 to be buttoned or secured at the backs thereof by which means I am enabled to avoid pressure of the closing means against the inside of the fingers of the operator. Other closing means not shown in the drawings, 75 may obviously also be employed within the scope of my invention, and it is evident that I am not restricted to the securing of the closing means in the immediate vicinity of the openings, but may secure them at any 80 distance thereof to suit the particular purpose for which my invention may be utilized. It is also evident that my invention is not limited to providing the openings merely 85 in the forefinger and thumb, but I may provide them at any other places of the glove to suit the various requirements.

What I claim is:—

1. A hand covering including thumb and finger members having overlapping seams 90 and with a cleft in one of the members remote from the seam, and a closure for the cleft extending at one edge between said overlapping seam portions and secured in position by the stitches of the seam. 95

2. A hand covering including thumb and finger members having overlapping seams and with a cleft in one of the members remote from the seam, a closure for the cleft 100 extending at one edge between said overlapping seam portions and secured in position by the stitches of the seam, and fastening means for securing the closure at its free edge to the cleft member.

In testimony whereof, I affix my signature hereto.

TARY PACIFICO.
